UNITED STATES PATENT OFFICE.

WILLIAM L. GORDON, OF ROME, GEORGIA.

MECHANISM FOR GIVING A COMBINED ROTARY AND RECIPROCATING MOTION TO CHURN-DASHERS.

SPECIFICATION forming part of Letters Patent No. 241,799, dated May 24, 1881.

Application filed March 8, 1881. (No model.)

To all whom it may concern:

Be it known that I, WILLIAM L. GORDON, of Rome, in the county of Floyd and State of Georgia, have invented certain new and useful 5 Improvements in Mechanism for Giving a Combined Rotary and Reciprocating Motion to Churn-Dashers; and I do hereby declare that the following is a full, clear, and exact description of the invention, which will enable others 10 skilled in the art to which it appertains to make and use the same, reference being had to the accompanying drawings, which form a part of this specification.

Figure 1 is a top plan. Fig. 2 is a vertical 15 sectional view, and Fig. 3 is a view of the dasher detached.

Corresponding parts in the several figures are denoted by like letters of reference.

This invention relates to that class of churns 20 in which the dasher has a combined rotary and vertical reciprocating motion; and it consists, especially, in the improved construction of the operating mechanism, as will be hereinafter more fully described, and particularly pointed 25 out in the claims.

In the drawings hereto annexed, A represents the base, which is provided with two uprights, B C, connected by a cross piece or brace, D. The upright B is provided, above the brace 30 D, with a slot or notch, E, in which is pivoted a lever, F, extending through a vertical slot, G, in the upright C. The brace D is provided with a central vertical bearing, H, for the stem or shaft I of the dasher J, which consists of 35 two cross-pieces, K, secured X-wise at the lower end of the stem or shaft, and provided on opposite sides with vertical pins or pegs L. By this construction of the dasher it is specially adapted to cut and agitate the cream by 40 the vertical reciprocating and rotary motion, which it is the object of the operating mechanism to produce.

A thermometer, M, is secured to the side of the dasher for the purpose of gaging the temperature of the cream.

N is a balance-wheel, provided with a radial slot, O, by which it may be adjusted in a horizontal position upon the dasher-stem, where it is secured by a pin or key, P, or any other suitable means.

Q Q are ropes or cords, the ends of which are secured to opposite sides of the collar of

the fly-wheel, from whence they pass through openings R in the brace D, at some distance from the dasher-stem. The ends of the cords 55 are then joined, as shown, under a stud, S, which prevents them from being exposed to the friction of the dasher-stem. The upper end of the latter is fitted in a recess or groove, T, in the under side of lever F, as shown. 60

U is a rubber spring, fitted adjustably upon upright C above the lever F, to receive the force of the upstroke of the latter and impart additional impetus to the operation. The end of the lever may be connected by a cord, V, with 65 the end of a treadle, W, hinged at the end of the base; or the lever may be operated by hand, if preferred.

From the foregoing description, taken in connection with the drawings hereto annexed, 70 the operation of my invention will be readily understood. The vessel containing the cream having been placed upon base A, between the uprights B C, the dasher and fly-wheel are turned until the cords Q Q are wound partly 75 upon the dasher-stem. By operating lever F the dasher is now vertically reciprocated, the arrangement of the fly-wheel and cords serving to rotate or oscillate the dasher with sufficient force or impetus to lift it when the lever 80 is raised, when, by a pressure of the lever, the motion is continued.

The construction of this device is simple and inexpensive, and it may be easily operated with 85 good results.

Having thus described my invention, I claim and desire to secure by Letters Patent of the United States—

1. The combination, with the dasher I, having slotted fly-wheel N, of the lever F, slotted 90 upright C, having spring U, and operating-cords Q Q, as herein described, for the purpose set forth.

2. The combination, with the dasher J, of the fly-wheel N, having slot O, substantially 95 as and for the purpose set forth.

In testimony that I claim the foregoing as my own I have hereto affixed my signature in presence of two witnesses.

WILLIAM L. GORDON.
